The ornamental design for continuous radius conveyor plates as shown and described.

DESCRIPTION

FIG. 1 is a front perspective view of continuous radius conveyor plates showing the new design;

FIG. 2 is a front elevational view of the continuous radius conveyor plates of FIG. 1;

FIG. 3 is a rear elevational view of the continuous radius conveyor plates of FIG. 1;

FIG. 4 is a right side plan view of the continuous radius conveyor plates of FIG. 1;

FIG. 5 a left side plan view of the continuous radius conveyor plates of FIG. 1;

FIG. 6 is a top plan view of the continuous radius conveyor plates of FIG. 1;

FIG. 7 is a bottom plan view of the continuous radius conveyor plates of FIG. 1; and,

FIG. 8 is a front elevational view of the continuous radius conveyor plates, shown in condition of use.

The broken lines in the drawings depict portions of the continuous radius conveyor plates that form no part of the claimed design.

The plates are shown with a symbolic break in its length and width. The appearance of any portion of the article between the break lines forms no part of the claimed design.
